MANCHESTER ELDIDGE AND FRANCIS A. REED, OF ALEXANDRIA,
VIRGINIA.

Letters Patent No. 64,002, dated April 23, 1867.

IMPROVEMENT IN GRAIN ELEVATOR AND DUMPING APPARATUS.

The Schedule referred to in these Letters Patent and making part of the same.

TO ALL WHOM IT MAY CONCERN:

Be it known that we, MANCHESTER ELDIDGE and FRANCIS A. REED, of Alexandria, in the county of Alexandria, and State of Virginia, have invented a new and improved Grain-Elevating and Dumping Apparatus; and we do hereby declare that the following is a full and exact description thereof, reference being had to the accompanying drawings, and to the letters of reference marked thereon.

This invention consists of a platform combined with a hoisting apparatus and vertical guide-bars, in such manner that grain or other material can be elevated to any desired height, and automatically dumped in an effectual and expeditious manner.

To enable those skilled in the art to make and use our invention, we will proceed to describe its construction and operation.

A represents upright posts set in a square in the foundation B, and constituting, in connection with the cross-beams C, a frame for the support of the machine. In common use this frame would be unnecessary, as the machine would be connected with hatchways in storehouses in the same manner as ordinary hoisting machines. D represents a platform consisting of any material suitable to the nature of the substance to be elevated, and of any desired size and shape. Connected with this platform by means of ears d, or in any other convenient manner, are chains or ropes E, of which, in this instance, there are four of equal length. The upper ends of these chains are joined, one to each of the ends of metallic bails F, the two chains on one side of the platform being joined to one bail, and the two on the other side to the other bail. These bails should be of a length about equal to the distance between the two ears d that are on the same side of the platform; as during the dumping process the bails are compelled to act as levers, and therefore should be as long as possible, in order to do the work required of them with the more ease. Each bail is provided with an eye, f, located at its centre, in order that when the platform is suspended by means of the cross-bail G, connecting the eyes f, it may hang in a horizontal plane. The eyes f also discharge another function in the dumping process, which will be described hereafter. The cross-bail G also has an eye, g, at its centre, for the purpose of receiving the rope H, by which the platform is elevated, which rope passes over a pulley, I, in the cross-beam K, at the top of the frame, and passing thence over the pulley I' in the same cross-beam, comes down to the platform, and passing under the sheave L terminates in a suitable apparatus for receiving a horizontal motion, as for instance, the whiffle-tree to which a horse is attached. m m represent swivels in two of the ears d, directly opposite each other. Through each of these swivels passes a vertical metallic rod, n, extending from the top to the bottom of the frame, near one corner thereof, and fastened at both ends so as to be immovable. These rods are the guides on which the platform travels. O represents stops on the rods n, each of which is provided with a set-screw, o, and a spiral spring, o', enclosing the rod n and extending downward from the stop as far as may be desired. These stops should both be located at the same height, their object being to check the upward progress of one side of the platform, in order that, the other side still ascending under the operation of the continued strain upon the rope H, the platform may assume an inclined position and its load be consequently dumped. The use of the spiral spring o' is to prevent the shock on the motor that would result from an instantaneous stoppage of one side of the platform when under full headway, as it would necessarily be, in order to insure an effectual dumping. To the eye of the cross-bail G is also attached one end of a rope, H', which, passing upward over the pulleys P and P' in the cross-beam K, is attached at its other end to a counterpoise, W, which is of a weight somewhat less than that of the platform, in order to assist in hoisting it, and at the same time not hinder the lowering of it. The counterpoise is enclosed in a vertical trunk, Q, to prevent its swaying at the end of the rope H', and to insure its regular action. The cross-beams C are supposed to represent the foundations of the second story of a building, and R represents a portion of the floor of the same. The stops O are so located that the side of the platform which comes to a stand shall be a little higher than the upper edge of the inclined plane S, which is placed so near the vertical guide-bars n, that the material elevated cannot do otherwise than pass from the platform to the inclined plane, and thence to the floor.

From this description the operation of the invention may be easily understood. The platform is maintained by suitable supports at a convenient height for loading during that operation, and having received its burden

the motor is put in operation and the platform elevated, the guide-bars, through the action of the swivels, directing its progress. As soon as its edge strikes the spring o' its speed begins to decrease, while the horse or other motor, suffering no shock, is enabled to continue its course and keep the cross-bail G in motion with undiminished velocity. The result is that the inner ends of the bales becoming fixed, the bails act as levers, their inner ends being the fulcrum. The power is applied through the cross-bail G at the eyes f , which also prevent the cross-bail from slipping along the bails. Under this application of power the outer edge of the platform continues to rise; the platform assumes an inclined position, the swivels m admitting of this motion, and the load of course slides off upon the inclined plane S to the floor R , whence it may be removed.

Having thus fully described our invention, what we claim, and desire to secure by Letters Patent, is—

1. The platform D and guide-bars n , in combination with the swivels m , which furnish pivots for the platform whereby it assumes alternate inclined and horizontal positions, substantially as described.
2. The guide-bars n , in combination with the spring o' and stops O , as and for the purpose set forth.
3. The hoisting and dumping apparatus, constructed as explained.
